TOY AIRPLANE

Edmund W. Baggott, Brooklyn, N. Y., assignor
to Ideal Novelty & Toy Co., Hollis, N. Y., a cor-
poration of New York

Application November 13, 1946, Serial No. 709,476

1 Claim. (Cl. 46—75)

1

This invention relates to a toy airplane and, more particularly, to a toy airplane of the helicopter type.

It is an object of the invention to provide a toy helicopter having a pair of coaxial propellers located above the fuselage thereof and so arranged as to rotate in opposite directions in parallel horizontal planes.

It is a further object of the invention to provide a toy helicopter provided with a pair of coaxial propellers adapted to rotate horizontally and in opposite directions and further provided with an additional propeller either at the front or rear of the fuselage adapted to rotate in a vertical plane simultaneously with the rotation of the first-mentioned pair of coaxial propellers.

It is another object of the invention to provide a toy airplane of the character indicated which can be fabricated easily and cheaply and which will be durable and attractive in appearance.

The above objects as well as additional objects and advantages will be readily apparent in the course of the following description taken in connection with the accompanying drawing, which illustrates a preferred embodiment of the invention, and wherein:

Fig. 1 is a central vertical longitudinal sectional view of a toy helicopter embodying the features of the invention and illustrating the interrelationship between the propellers and their respective rotary elements;

Fig. 2 is a sectional view taken along line 2—2 of Fig. 1;

Fig. 3 is a fragmentary bottom plan view partially broken away to illustrate the engagement between the beveled driver element fixed to the undercarriage axle and the rotary horizontal follower element fixed to the shaft of the topmost, horizontally rotating propeller;

Fig. 4 is a fragmentary plan view illustrating the engagement between the rotary vertical element fixed to the shaft of the vertically rotating propeller and the lower rotary horizontal follower element fixed to the shaft of the uppermost horizontally rotating propeller;

Fig. 5 is an enlarged fragmentary detail clearly illustrating the engagement between the vertical rotary element of the vertically rotating propeller and the horizontal rotary element of the topmost, horizontally rotating propeller.

Referring now to the drawings in detail, the toy helicopter has a fuselage 10 which may be conveniently molded from any suitable synthetic plastic or other material and which comprises a

2

top shell portion 10a and a bottom shell portion 10b. Wheel-suspension brackets 11 may be formed integrally with the bottom shell portion 10b, and bottom shell portion 10b may be formed adjacent its rear end with a downwardly projecting, fin-like tail rest 12. A pair of undercarriage wheels 13 are mounted on an axle 14 between the brackets 11.

Top shell portion 10a is formed medially with respect to the sides thereof and in the region above the brackets 11 with a housing 15, projecting partially upwardly from the surface of said shell portion and projecting partially downwardly between the side walls thereof, having a bore extending vertically therethrough for the reception of a hollow propeller shaft 16 carrying a propeller 17 at the upper end thereof. Affixed to the lower end of hollow shaft 16 is a rotary element 18 which may take the form of a bevel gear or which may alternatively have on its bottom surface an annular V-shaped groove 18a presenting knurled engagement surfaces 18b, as illustrated in Fig. 2. A coaxial propeller shaft 19 carrying a propeller 20 at the upper end thereof is journaled in hollow shaft 16 and extends below rotary element 18 for a fixed predetermined distance. Affixed to the lower end of propeller shaft 19 is a rotary element 21 which may take the form of a bevel gear or which may alternatively have on its upper surface an annular V-shaped groove 21a, presenting knurled engagement surfaces 21b in a manner similar to that described for rotary element 18.

A vertical rotary element 22 mounted at one end of a horizontal shaft 23 is interposed between rotary elements 18 and 21 and is preferably in the form of a bevel wheel presenting oppositely inclined knurled engagement surfaces 22a in abutment against the respective knurled engagement surfaces 18b and 21b of the opposed V-shaped grooves 18a and 21a in horizontal rotary elements 18 and 21. Horizontal propeller shaft 23 is supported by a slotted holding fork 24 or other means extending downwardly from an integral with top shell portion 10a. Propeller shaft 23 extends rearwardly between top shell portion 10a and bottom shell portion 10b and for a short distance beyond the tail of the fuselage at which point it carries a vertically rotatable propeller 25. In this connection it is to be noted that tail rest 12 should be of sufficient height to clear the blades of propeller 25 off the ground line in order to permit free rotation thereof.

Rotary element 21 has on its bottom surface a

V-shaped groove 21c similar to groove 21a in its upper surface and also presenting knurled engagement surfaces 21d for a purpose to be hereinafter described.

A beveled driver element 26 is secured at a proper point along undercarriage axle 14 parallel to wheels 13 and presenting knurled surfaces 26a engageable against knurled surfaces 21d of groove 21c in the underside of rotary element 21. Driver element 26 is permanently fixed to axle 14 in any desired manner and rotates simultaneously with the rotation of said axle and the wheels 13, its engagement with the groove 21c of rotary element 21 being effected by a suitably disposed slot or opening 27 in bottom shell portion 10b.

In actual operation, as the toy airplane is moved manually forwardly along the ground, undercarriage wheels 13 and driver element 26 are caused to rotate in a counterclockwise direction (in the direction of arrow of Fig. 1). The rotation of driver element 26 in a counterclockwise direction in turn causes the rotation of rotary element 21 directly engaged therewith and the simultaneous rotation of upper horizontal propeller 20, in a counterclockwise direction as seen from below, the direction of rotation of propeller 20 being illustrated in Fig. 1 by an associated arrow. The counterclockwise rotation of rotary element 21 is accompanied by counterclockwise rotation (viewed from the front of the airplane) of vertical rotary element 22 interposed between horizontal rotary elements 21 and 18 and thus causes counterclockwise rotation (again viewed from the front of the airplane) of vertically rotatable propeller 25 attached to element 22 through shaft 23. In turn the counterclockwise rotation of vertical element 22 is accompanied by the clockwise rotation (as seen from below) of upper rotary element 18 directly engaged therewith and the simultaneous rotation of lower propeller 17 in the same direction (clockwise as seen from below). It is thus seen that by pushing the toy airplane forwardly along the ground the horizontal propellers 17 and 20 are made to rotate in parallel planes in opposite directions along with simultaneous rotation of the vertically rotatable propeller 25. Obviously, pushing the airplane rearwardly along the ground would reverse the direction of rotation of the propellers.

It should be noted that the vertically rotatable propeller 25 might be located at the front of the plane instead of at the rear as illustrated in the drawings or might be omitted and that also the horizontal rotary elements 18 and 21, the interposed vertical rotary element 22 and driver element 26 might vary in structure from the particular embodiment illustrated, one such possible modification taking the form of bevel gears, as has been mentioned hereinabove.

The top shell portion 10a and the bottom shell portion 10b may be secured together adhesively or in any other suitable manner. Where adhesive is used the provision of conventional related, cooperating lugs and recesses is desirable. With the possible exception of the propeller shaft and undercarriage axle, the component parts may be fabricated in the same or contrasting colors from any suitable plastic material.

10 Since certain additional modifications may be made in the toy airplane of my invention without departing from the scope thereof, it is intended that all matter contained in the foregoing description and shown in the accompanying drawing be interpreted merely as illustrative and not in a limiting sense.

I claim:

20 A toy airplane which has a hollow body which is provided with an upstanding bearing, a hollow upstanding shaft located in said bearing and extending above said body, an inner upstanding shaft extending through and above said hollow shaft, said shafts having respective superposed propellers above said body, a hollow-shaft rotor 25 fixed to said hollow shaft below said bearing, said hollow-shaft rotor having a bore, said inner shaft extending through and below said bore, an inner-shaft rotor fixed to said inner shaft below said hollow-shaft rotor, said body having a wheel-shaft 30 turnably connected thereto at its bottom, wheels fixed to said wheel shaft, said wheel-shaft having a wheel-shaft driving rotor which extends upwardly into said hollow body, said inner-shaft rotor abutting said wheel-shaft rotor, a longitudinal propeller shaft which extends longitudinally through said body and which has a propeller fixed thereto externally of said body, an intermediate rotor fixed to said longitudinal propeller shaft and abutting the underside of said hollow-shaft 40 45 rotor and the upper side of said inner-shaft rotor, said intermediate rotor being spaced from the common axis of said hollow shaft and said inner shaft, all said rotors being located in said hollow body, said wheel-shaft rotor being a support for said other rotors.
